UNITED STATES PATENT OFFICE

2,264,873

CONTROL SYSTEM

William D. Cockrell, Schenectady, N. Y., assignor
to General Electric Company, a corporation of
New York

Application July 12, 1940, Serial No. 345,427

12 Claims. (Cl. 250—27)

This invention relates to control systems, more particularly to time delay systems for initiating a controlling operation in response to a signal after a predetermined interval of time.

More specifically, the invention relates to a time delay device of the character described in which the time interval is inversely proportional to the speed of a moving element minus a fixed time.

One application of a device of this character is its use in connection with a photoelectric device for detecting and marking the location of pinholes in a steel strip. In this pinhole detector application, the sheet is marked by a magnetically actuated marking device located a short distance from the photoelectric detector in the direction of the travel of the strip. The strip may travel at any speed from a low speed such as 100 feet per minute to a higher speed, such for example as 900 feet per minute. Since the magnetic marking device requires a fixed time to strike the strip after its coil has been deenergized, the time delay device is required to introduce a time delay in the operation which is inversely proportional to the speed of the strip minus a fixed time. Such a time delay is expressed by the equation

$$T = \frac{K}{S} - a$$

in which T represents the time delay, S represents the speed, and K and a are constants.

In carrying the invention into effect in one form thereof, the time inversely proportional to speed minus the fixed time is obtained by charging a capacitor with a constant current the value of which is proportional to the speed of a moving element and adding to the voltage of the capacitor a voltage produced by this charging current flowing through a resistor. The circuit is arranged so that when the sum of these two voltages attains a predetermined value, a controlling operation is initiated.

In illustrating the invention in one form thereof, it is shown as embodied in a photoelectric pinhole detecting and marking device. It will be understood, however, that the invention has other applications.

For a better and more complete understanding of the invention, reference should now be had to the following specification and to the accompanying drawing in which Fig. 1 is a simple, diagrammatical sketch of an embodiment of the invention, and Fig. 2 is a diagrammatic view in perspective illustrating an application of the invention.

Referring now to the drawing, a strip of steel 10 is being moved in the direction indicated by the arrow to a flying shear (not shown). Rolls 11 are in contact with the strip 10 and consequently the peripheral speed of these rolls is equal to the linear speed of the strip.

A scanning unit 12 is provided for detecting the presence of pinholes in the strip. This scanning unit comprises two rectangular metal boxes hinged together with a space between to accommodate the strip. The upper box contains the light source lamps 13 and lens system. The lower box contains the photoelectric cells, amplifier tubes and associated circuits mounted on a panel. A lens system similar to that in the upper box is also provided. The scanner is equipped with a pair of shutters (not shown) which provide for operation with any width of strip within predetermined limits. The structural details of the scanner do not constitute any part of the present invention. Scanning units of this character are well understood devices. They are procurable upon the market and are described in printed publications and patents. For example, a scanning unit of this character is described in United States Patent No. 2,193,590 Gulliksen. It is sufficient to understand that when a pinhole in the strip passes through the scanner, an impulse of positive voltage is applied to the conductor 14, i. e. the potential of conductor 14 becomes positive with respect to the negative side 16 of the direct-current source 15, 16 for a few thousandths of a second. This signal voltage sets the device in operation.

A magnetic marking device 17 is mounted a short distance away from the scanner in the direction of the travel of the strip and near the edge of the strip. This marking device serves to place a mark on the edge of the strip when a pinhole has been detected. Normally, the solenoid 17a is energized and maintains the marking element 17b out of engagement with the strip.

The marker solenoid 17 is connected in the anode-cathode circuit of a suitable electric valve 18. This valve is preferably a "hard" tube of a type known to the art as a "beam" tube. As shown in the drawing, the anode of the electric valve 18 is connected through solenoid 17 to the positive side 15 of the direct-current source and the cathode is connected to the negative side 16 of the source. The screen grid 18a is connected to the positive side of the source and is thus given a positive bias, and grid 18b is connected through resistor 19 to the negative side 16 of the source. Thus, the control grid 18b is at the cathode po-

tential and consequently the tube is normally conducting and solenoid 17 is normally energized.

A twin triode electric valve 20 is also connected across the source 15, 16. This valve is normally biased through the anode resistor 21 and the grid voltage divider resistors 22 and 23 so that the grid bias as measured between points 22a and 24 is approximately zero, and therefore the total tube current flows through the left-hand path of the triode and through its cathode resistor 25. A resistor 21 and a capacitor 27a are connected across source 15, 16 to filter the voltage supplied to valve 20 and other control valves connected to conductor 15a.

Another twin triode electric valve 26 is connected across the source 15, 16. The anodes are connected to the positive conductor 15a which is connected through filter resistor 21 to the positive side 15 of the source and the cathodes are connected to the negative side 16 of the source through resistors 28, 29 and 30, tachometer generator 31, resistors 32 and 33 and capacitor 34. Other types of tubes with high transconductance would be equally as satisfactory as electric valve 26. Tachometer generator 31 is driven from the rolls 11 and consequently it generates a voltage proportional to the speed of the strip which is applied to the grid of valve 26. The positive terminal of the generator is connected to the grid.

A current that is very closely proportional to the strip speed is caused to flow in the circuit of electric valve 26. The current is maintained constant for any given tachometer generator voltage because any tendency for the current to change such as caused by a variation in anode voltage is accompanied by a change in the voltage drop across resistors 28 and 29. This change in the voltage drop across these resistors is applied to the grid and produces a current change in the opposite direction. The overall result is that the current is maintained substantially constant for a wide range of anode voltages and tube characteristics.

The grid bias battery 35 is not absolutely essential to the invention, but it performs a very useful function. It keeps the grid voltage close to its average negative operating characteristic thereby permitting the tachometer generator voltage to be approximately equal to the voltage across resistors 28 and 29, and this has the effect of extending the linear variation of the tube current to low values of tachometer voltage.

Capacitor 36 and resistor 38 act as a filter to smooth out any ripple in the voltage of the tachometer generator such as might be produced by its commutator.

Capacitor 34 is the timing capacitor which is charged by the constant current supplied by electric valve 26. This same charging current also flows through the fixed resistor 33 and the adjustable resistor 32 to provide the voltage which is added to the voltage of the capacitor to compensate for the fixed time of the operation of the marker. Since the actual operating speeds of different markers vary, the adjustable resistor 32 is provided to adjust the circuit accurately when the installation is completed.

An electric valve 37 is connected in parallel with capacitor 34, i. e. its anode is connected to one terminal of the capacitor and the cathode to the other. This valve is preferably of the "beam" or pentode type in which the anode may operate successfully at a minimum voltage positive with respect to the cathode. In the normal

steady state condition, the grid 31a of valve 37 is approximately at cathode potential which causes the valve to conduct. This results in practically short circuiting the timing capacitor 34 and in maintaining the voltage across the capacitor at a very low value.

A thyratron tube 38 is also connected across conductors 15, 16. Resistor 39 is connected between the anode and the side 15 of the source, and the cathode is connected through resistors 40, 41 and voltage divider resistor 42 to the negative side 16 of the source. Normally, the thyratron tube conducts no anode current because its grid is held negative with respect to its cathode by the voltage drop across the devider resistor 42.

With the foregoing understanding of the apparatus and its organization, the operation will readily be understood from the following description.

When a pinhole in the strip passes through the photoelectric cell detecting unit 12, light falls for a brief instant of time on one of the photoelectric cells. This produces an electrical impulse, i. e. a sudden positive variation in the voltage between 14 and the negative side 16 of the source which is applied to the grid of the thyratron 38 and as a result the thyratron becomes conducting. From the time the light falls on the photoelectric cell until the thyratron becomes conducting is so brief that the two events occur practically simultaneously. When current passes through the voltage dropping resistor 38, the voltage of the junction point 38a drops from its normal steady state value to a very low value. For example, the steady state potential of this point may be 300 volts and when the current is flowing, the potential may drop to a value of less than 20 volts.

This resultant potential change is transferred to the timing circuit through the capacitor 43. More specifically, the decrease in voltage of point 38a allows capacitor 43 to discharge with the result that the voltage of grid 31a becomes so negative with respect to the cathode that the valve ceases to conduct and the constant current flowing in the output circuit of valve 26 begins to charge the capacitor 34. This charging current is maintained constant at a value proportional to the speed of the strip in the manner set forth in the foregoing description.

As the capacitor 34 becomes charged, the voltage across the capacitor increases and as this voltage increases, the voltage of the junction point 32a also increases. After an interval of time which is inversely proportional to the speed of tachometer generator 31 minus a fixed time, the voltage of the grid 28a to which the point 32a is connected attains a value at which the right-hand path of the valve 26 begins to conduct and causes current to flow through the resistor 21. As a result of this the voltage of point 21a which is connected to grid 28b is decreased to such an extent that the left-hand path of valve 26 ceases to conduct current, and the current of the left-hand path is transferred to the right-hand path. As a result of the large current which now flows through resistor 21, the voltage of point 21a is suddenly decreased to a low value. This sudden decrease in voltage of point 21a is transferred through capacitor 44 to the grid 18b of valve 18. As a result the voltage of grid 18b becomes so negative with respect to its cathode that valve 18 ceases to conduct current and the solenoid 17 of the marker is de-

energized. After the fixed time required for the marker element 17 to drop to the strip, the surface of the strip is suitably marked as by knurling at the edge of the strip. If all the adjustments have been properly made, the mark will be made at a distance from the detector equal to the distance of the pinhole from the detector so that the pinhole may be readily located.

That the time interval interposed by the timing circuit between the signal voltage and the deenergization of valve 18 to release the marker is inversely proportional to the speed of the strip minus a fixed time may be demonstrated mathematically as follows:

Let

e =the voltage across resistors 32 and 33 and capacitor 34,

E =the tripping voltage, i. e. the grid voltage required to render the right-hand path of valve 26 conducting,

S =speed of the tachometer generator 31 or the speed of the strip 10,

R =ohmic resistance of resistors 32 and 33,

C =capacitance of capacitor 34.

Then,

(1) $i = NS$ in which i is the constant current from valve 26 which charges capacitor 34 and N is a constant.

$$(2) \quad e = e_c + e_r - C i t + R i$$

or

$$t = \frac{e - R i}{C i} = \frac{e}{C i} - \frac{R}{C}$$

Consequently for the time T to trip at a fixed limit voltage E ,

$$(3) \quad T = \frac{E - R}{C i - C}$$

and substituting from (1)

$$T = \frac{E}{C N S} - \frac{R}{C}$$

Since E , R , C and N are constants

$$\frac{E}{C N} \text{ is also a constant} = K \text{ and}$$

$$\frac{R}{C} = a$$

Thus

$$T = \frac{K}{S} - a$$

In other words, T is a time which is inversely proportional to the speed of the strip minus a fixed time.

At the instant of the removal of voltage from marker solenoid 17, voltage is also removed from the coil of "reset" relay 45. Relay 45, however, does not drop out instantly because of the capacitor 46 which is connected across its coil. The brief interval during which the reset relay is held picked up is sufficient to permit the plunger of the marker solenoid to drop out completely before the reapplication of power.

When the contacts 45a of relay 45 do open, and interrupt the anode circuit of the thyratron 38, the thyratron becomes non-conducting. Resistor 47 and capacitor 48 form a highly damped 70 oscillatory circuit to insure the positive circuit break and minimum surge on remake. In response to the interruption of current in the anode-cathode circuit of thyratron 38, the IR drop across resistor 39 disappears, and point 75

39a regains the positive potential of the side 15 of the source. As a result, capacitor 43 is subjected to a greatly increased voltage and charges rapidly. This causes the voltage of the grid 37a of valve 37 to become more positive, thereby to render the valve 37 conducting so that capacitor 34 is again short circuited and thereby rapidly discharged. The resulting decrease in voltage across the capacitor 34 causes the potentials of the point 32a and of the grid 26a of valve 26 to become increasingly negative with the result that the right-hand path of valve 26 becomes non-conducting. The interruption of current in the right-hand path of valve 26 causes the IR drop across resistors 27 and 21 to disappear so that the potential of point 21a attains a high positive value, thereby increasing the voltage across capacitor 44. As capacitor 44 charges, the grid 26b of valve 26 becomes increasingly positive so that the left-hand path of valve 26 again becomes conducting. Simultaneously, the voltage of grid 18b becomes more positive and causes the valve 18 to become conducting, thereby to energize the marker operating solenoid 17 to retract the marker and also to energize solenoid 45 of the reset switch which thereupon recloses its contacts 45a. This terminates one complete timing cycle, and the system is now in its steady state condition and is thus reset for a subsequent operation.

Resistor 29 is made adjustable to provide a means for varying the charging current for a given tachometer voltage. The resultant variation in the time delay in the operation of the marker makes it possible to use this control for adjusting the distance that the pinhole will move forward before the strip is marked. This is desirable because it permits the marker to be installed at various distances from the scanner.

Although in accordance with the provision of the patent statutes this invention is described as embodied in concrete form and the principle thereof has been described together with the best mode in which it is now contemplated applying that principle, it will be understood that the apparatus and connections shown and described are merely illustrative and that the invention is not limited thereto, since alterations and modifications will readily suggest themselves to persons skilled in the art without departing from the true spirit of this invention or from the scope of the annexed claims.

What I claim as new and desire to secure by Letters Patent of the United States is:

55. 1. A device for producing a time delay inversely proportional to the speed of a moving element minus a fixed time comprising an electrical energy storage device, means responsive to a signal for initiating the supply of current to said energy storage device, means for maintaining said current substantially constant at a value proportional to said speed, means for supplying a voltage proportional to said fixed time to the circuit of said energy storage device, and means responsive to the sum of said voltage and the voltage across said energy storage device for initiating a controlling operation when the sum of said voltages attains a predetermined value.

60. 2. A device for producing a time delay inversely proportional to the speed of a moving element minus a fixed time comprising a substantially discharged capacitor, means responsive to a signal for initiating the supply of current to said capacitor to increase the voltage across said capacitor, means for maintaining said current con-

stant at a value proportional to said speed, means for supplying a voltage proportional to said fixed time to the circuit of said capacitor, and means responsive to the sum of said voltages for initiating a controlling operation when the sum of said voltages attains a predetermined value.

3. A device for producing a time delay inversely proportional to the speed of a moving element minus a fixed time comprising a capacitor, a resistor connected in series relationship with said capacitor, means responsive to a signal for initiating a supply of current through said resistor to said capacitor thereby to increase the voltage across said capacitor, means for maintaining said current constant at a value proportional to said speed, means for supplying a voltage proportional to said fixed time to the circuit of said capacitor, and means responsive to the sum of said voltages for initiating a controlling operation when the sum of said voltages attains a predetermined value.

4. A device for initiating a controlling operation in response to a signal an interval of time after said signal that is inversely proportional to the speed of a moving element minus a fixed time comprising a control circuit, an electrical energy storage device connected in said circuit, means for short circuiting said energy storage device prior to said signal, means for introducing a voltage in said circuit proportional to said fixed time, means for causing a current to flow in said circuit proportional to the speed of said element, means responsive to said signal for interrupting the short circuit about said energy storage device thereby to cause said current to store electrical energy in said storage device and to produce an increasing voltage across said storage device, and means responsive to the sum of said voltages for initiating said controlling operation when said sum equals a predetermined value.

5. A device for initiating a controlling operation in response to a signal an interval of time after said signal proportional to the speed of a moving element minus a fixed time comprising a control circuit, a capacitor connected in said circuit, means for causing a current to flow in said circuit, means for short circuiting said capacitor prior to said signal, means for introducing a voltage in said circuit proportional to said fixed time, means responsive to said signal for rendering said short circuiting means ineffective, means for maintaining the current in said circuit substantially constant at a value proportional to the speed of said element so that the voltage across said capacitor is caused to increase, and means responsive to the sum of said voltages for initiating a controlling operation when said sum attains a predetermined value.

6. A control system for initiating a controlling operation in response to a signal an interval of time after said signal proportional to the speed of a moving element minus a fixed time comprising a control circuit, a capacitor in said circuit, a resistor connected in series with said capacitor, means for causing a current to flow in said circuit, means for short circuiting said capacitor prior to said signal, means responsive to said signal for rendering said short circuiting means ineffective, means for maintaining the current of said circuit substantially constant at a value proportional to the speed of said element whereby the voltage across said capacitor is increased, and means responsive to the sum of the voltages across said capacitor and said resistor for initiat-

ing a controlling operation when said sum equals a predetermined value.

7. A control system for initiating a controlling operation in response to a signal a time interval after said signal that is proportional to the speed of a moving element minus a fixed time comprising a control circuit, a capacitor and an adjustable resistor connected in series relationship in said circuit, means for causing a current to flow in said circuit, means for short circuiting said capacitor prior to said signal, means for maintaining the current in said circuit substantially constant at a fixed value proportional to the speed of said element, said resistor being adjusted so that the voltage drop across said resistor is proportional to said fixed time, means responsive to said signal for rendering said short circuiting means ineffective whereby said capacitor is charged and the voltage across said capacitor is increased, and means for initiating a controlling operation when the sum of said voltages attains a predetermined value comprising a second control circuit including an electric valve having its grid circuit connected across said capacitor and said resistor.

8. A time delay device comprising in combination a control circuit, a capacitor and a resistor included in said circuit, means for causing a current to flow in said circuit, an electric valve connected across said capacitor, control means for rendering said valve conducting thereby to short circuit said capacitor, means including a tachometer generator connected in said circuit for maintaining the current in said circuit substantially constant at a value proportional to the speed of said generator, means responsive to a signal for rendering said short circuiting means ineffective whereby said capacitor is charged and the voltage across said capacitor is increased, and means responsive to the sum of the voltages across said capacitor and resistor for initiating a controlling operation after an interval of time required for the sum of said voltages to attain a predetermined value.

9. A time delay device comprising in combination a control circuit, a capacitor and an adjustable resistor included in said circuit, means for causing a current to flow in said circuit, means for short circuiting said capacitor, means including an electric valve and a tachometer generator included in said circuit for maintaining the current in said circuit substantially constant at a value proportional to the speed of said generator, means responsive to a signal for rendering said short circuiting means ineffective so that said capacitor is charged and the voltage across said capacitor is increased, and means responsive to the sum of the voltages across said capacitor and resistor for initiating a controlling operation after an interval of time required for the sum of said voltages to attain a predetermined value.

10. A time delay device comprising in combination a control circuit, a capacitor and a resistor included in said circuit, means for causing a current to flow in said circuit, a first electric valve connected in parallel with said capacitor and connected to be conducting for short circuiting said capacitor, means for maintaining the current in said circuit substantially constant at a value proportional to the speed of a moving element, a second electric valve connected to be non-conducting, means for applying a signal voltage to the grid of said non-conducting valve to render said valve conducting, means including a connection from the anode-cathode circuit of said second valve to the grid circuit of said first

valve for rendering said first valve non-conducting so that said capacitor is charged and the voltage across said capacitor is increased, means responsive to the sum of the voltages across said capacitor and resistor for initiating a controlling operation after a time interval required for the sum of said voltages to attain a predetermined value, and means responsive to said controlling operation for rendering said second valve non-conducting thereby to reset said time delay device for a subsequent operation.

11. A time delay device comprising in combination a control circuit, a capacitor and a resistor connected in said circuit, a first electric valve connected in parallel with said capacitor, means for applying voltage to the grid of said valve to render it conducting thereby to short circuit said capacitor, a second electric valve, means for applying a voltage to the grid of said second valve to render said second valve non-conducting, means for applying a signal voltage to the grid of said second valve to render said second valve conducting, a connection from the anode-cathode circuit of said second valve to the grid circuit of said first valve for rendering said first valve non-conducting in response to current in the anode-cathode circuit of said second valve thereby to cause said capacitor to be charged and the voltage across said capacitor to increase, and electric valve means responsive to the sum of the voltages across said capacitor and resistor for initiating a controlling operation after an interval of time required for the sum of said voltages to attain a predetermined value.

12. A control system for initiating a controlling operation in response to a signal an interval of time after said signal proportional to the speed of a moving element minus a fixed time comprising a control circuit, a capacitor and a first adjustable resistor included in said circuit, means including a first electric valve included in said circuit for controlling the current in said circuit, means comprising a tachometer generator driven by said element and a second adjustable resistor connected in the anode-cathode circuit of said valve and a connection from said anode-cathode circuit to the grid of said valve for maintaining the current in said control circuit substantially constant at a value proportional to the speed of said element, said first resistor being adjusted to a value such that its voltage drop is proportional to said fixed time, a second electric valve having its anode-cathode circuit connected in parallel with said capacitor, means for applying a voltage to the grid circuit of said second valve to render said second valve conducting thereby to short circuit said capacitor, means for applying a signal voltage to the grid circuit of said second valve thereby to render said second valve non-conducting so that said capacitor is charged and the voltage across said capacitor is increased, and means responsive to the sum of the voltages across said capacitor and first resistor for initiating a controlling operation when the sum of said voltages attains a predetermined value.

WILLIAM D. COCKRELL.
